BOLT CUSHIONING DEVICE

Halvor Olsen Eiane, Washington Island, Wis.

Application August 4, 1938, Serial No. 223,020
In Canada August 6, 1937

2 Claims. (Cl. 42—1)

My invention relates to improvements in breech mechanism of automatic fire-arms and relates particularly to my earlier invention of an Automatic rifle, on which application for patent was filed June 1, 1936, Serial No. 82,811, in which a bolt handle is used for manipulation of the breech bolt for insertion of the initial cartridge into the cartridge chamber and for similar functions, etc., and the objects of my improvements are; first, to reduce to a minimum the tendency of the bolt handle to rebound when operated by automatic means; second, to prevent crystallization of the metal in the bolt handle and breech bolt by cushioning the abrupt stop of the bolt handle when brought in contact with a receiver of a gun by means of a wooden plug giving the same effect as produced by a wooden mallet striking against an object of steel or iron.

I attain these objects by the use of a wooden plug hereinafter more fully described and claimed having reference to the accompanying drawing, in which: Fig. 1 is a longitudinal side view of a breech bolt with the bolt handle raised in vertical position and showing location of the cushion plug. Fig. 2 is a rear end view of the breech bolt with its bolt handle turned down and showing by dotted lines location and shape of plug and its socket in the bolt handle.

A in Figs. 1 and 2 is the breech bolt in detached relation, such as used in my automatic rifle, shown and described in the aforementioned application for patent. 2 in Figs. 1 and 2 is the bolt handle, used for manipulating the bolt in the operation of loading an initial cartridge into a cartridge chamber of a gun, etc.

3 is the cushion plug, shown endwise in Fig. 1, which is adapted to strike against a flat faced seat in the receiver of applicant's automatic rifle, heretofore referred to.

40 The face of the plug 3 extends slightly beyond the outlines of the bolt handle 2, as shown in Fig. 2, and thus prevents metal from striking against metal and thereby reduces the tendency of the bolt handle 2 to rebound when brought to an abrupt stop in its automatic closing operation.

The dotted lines 4 in Fig. 2, indicate the shape and length of the wooden plug 3, as well as the socket into which the plug is inserted.

The wooden plug 3 is made of hardwood with the grains lengthwise and driven tight into its socket in the bolt handle 2.

Previous to insertion in the socket of the bolt handle 2, the plug 3 is first soaked in thin non-gumming oil which by reason of friction in the numerous thin pores in the wood produce a very efficient shock absorbing medium, and at the same time prevents crystallization of the metallic parts concerned.

While the primary object of the present invention is for use in my earlier invention heretofore referred to, the invention is none the less suitable for any automatic gun mechanism in which a bolt handle rotates with the breech bolt, irrespective of shape or size.

Having thus described my invention, what I claim as new and desire to secure by Letters Patent is:

1. In a breech bolt for an automatic fire-arm, a bolt-handle projecting from said breech-bolt, said breech-bolt adapted for longitudinal and rotary movements, a socket hole bored into said bolt-handle from the underside thereof and adjacent to the breech-bolt, a wooden plug inserted into said socket, said wooden plug adapted to cushion the force of the rotary blow of said bolt-handle and breech-bolt when brought to an abrupt stop against a receiver of a fire-arm.

2. In a breech-bolt for an automatic fire-arm, a bolt-handle projecting from said breech-bolt, said breech-bolt adapted for longitudinal and rotary movements, a socket bored into said bolt-handle from the underside thereof and adjacent to the breech-bolt, a wooden plug inserted into said socket, said wooden plug soaked in thin non-gumming oil adapted to cause friction while moving under a blow through the numerous pores in the wood of said plug whereby shock-absorbing qualities are produced to absorb the force of the rotary movement of said bolt-handle and breech-bolt when brought to an abrupt stop against a receiver on a fire-arm whereby the tendency of the bolt-handle to rebound is reduced to a minimum.

HALVOR OLSEN EIANE.
